UNITED STATES PATENT OFFICE

LINDSAY THORNE CRABBE, OF CHICAGO, ILLINOIS, ASSIGNOR TO PHOENIX-HERMETIC COMPANY, OF CHICAGO, ILLINOIS, A CORPORATION OF NEW YORK

ADJUSTABLE WRENCH

Application filed December 29, 1927. Serial No. 243,347.

This invention relates to wrenches, and more particularly to device of this type which are capable of adjustment and locking in adjusted positions.

Many kinds of adjustable wrenches have heretofore been proposed, but according to the present invention a construction is presented in which two major parts are employed, and these may be cheaply and quickly manufactured by punching and drop forging operations. The device is adapted for use for the removal of screw caps from glass jars, as a pipe wrench, or for other and similar purposes.

The device is illustrated in two forms of construction on the accompanying drawing by way of example, but it will be understood that the illustrated forms are not limitations upon the employment of the invention.

In these drawings:

Figure 1 is a plan view of an adjustable wrench according to this invention.

Fig. 2 is a section on line 2—2 of Fig. 1.

Fig. 3 is a fragmentary plan view of a modified form of the wrench.

Fig. 4 is a section on line 4—4 of Fig. 3.

On these drawings, in Figs. 1 and 2 is shown a wrench made of only three parts. The first member comprises a handle 10, a jaw member 11 which is formed integrally with the handle 10, and a sector 12 having the teeth 13 thereon arranged concentrically about a stop member 14, which in the construction shown is a rivet passed through the first member 10, 11, 12. A bottle top remover is formed on this first member by cutting it away to form a notch 15 with the lifting finger 16.

The second member includes the movable jaw 17 having an adjusting portion 18 formed integrally therewith. The adjusting portion at the end opposite the jaw 17 has an L-shaped slot 19, one leg of the L extending substantially parallel to the direction of the length of the jaw 17, while the other leg of the L is substantially at right angles thereto, and directed away from the stationary jaw 11. The third member or stop 14 passes through this slot and has an enlarged head to prevent the withdrawal of the movable

body 17 and its adjusting portion 18 from assembly with the first member 10, 11, 12. It is preferred to have the movable jaw 17 proper offset from the adjusting portion 18, so that it is in the plane of the fixed jaw 11. Between the jaw 17 and the slot 19 the adjusting portion is provided with a dog 20 which is formed from its material and is punched out of the plane of the adjusting portion, and is at such a position that when the stop 14 is in the position shown in Fig. 1, this dog 20 is engaged between teeth 13 of the sector 12; while if the stop 14 is at the other end of the slot 19, the dog 20 is free of all of the teeth 13. The end of the dog 20 is an extension 21 which fits against the surface of the tooth sector 12 and thus cooperates with the enlarged head of the stop 14 in holding the blades in the same plane.

The method of employment and adjustment of this device is as follows: By pressing upward on the outer end of the movable jaw 17, (Fig. 1) this jaw and its adjusting portion 18 is rocked counterclockwise substantially about an axis formed by the dog 20, whereby a relative movement of the stop and L-shaped slot occurs so that the movable jaw may be slid lengthwise toward the right in Fig. 1, thus freeing the dog 20 from the teeth 13. The movable jaw 17 is now free to rock in either direction about the stop 14 as a pivot so that it may be adjusted with respect to the fixed jaw 11. When a desired adjustment has been obtained, the movable jaw 17 is again slid toward the left in Fig. 1, and its dog 20 is engaged between two of the teeth 13. A clockwise movement of the movable jaw 17 will now bring the L-shaped slot and stop 14 again to the position shown in Fig. 1. It will be noted that the pressure of an article being gripped between the jaws 11, 17 will be exerted about the dog 20 as a fulcrum to retain the stop 14 in the indicated position.

In the modified form of Figs. 3 and 4 the handle 10, fixed jaw 11, sector 12 and teeth 13 are the same as before, and the movable jaw 17 again has the adjusting portion 18 with the slot 19 to engage the stop 14. The dog here provided is a rivet 30 secured in

the adjusting portion 18 of the movable jaw, having a square shank 31 and an enlarged head 32. This square shank 31 engages between the teeth 13 of the sector 12 as before, and the enlarged head 32 cooperates with the stop 14 to hold the movable jaw and fixed jaw in the same plane during operation. The operation of this modified form is the same as that described heretofore.

10 In each of these forms of execution the dog 20 and the stop 14 are spaced away from each other so that a long leverage is afforded to resist pressure against the movable jaw 14, so that a light and strong wrench may be made from relatively thin material.

15 It is obvious that the invention is not limited to the illustrative form, but that it may be modified in many ways within the scope of the appended claims.

20 What is claimed as new is:

1. In a device of the class described, a first member having a handle, a stationary jaw and a toothed sector; a second member having a movable jaw and an adjusting portion and a dog offset from the plane of said adjusting portion, said adjusting portion having an L-shaped slot therein; and a stop member on said first member to engage in said slot; so that when said second member is moved until the stop is at one end of said slot, the dog is disengaged from the teeth of said sector and the movable jaw may be moved toward or from the stationary jaw; and so that when the second member is moved until the stop is at the other end of said slot, the dog is engaged between teeth of said sector and the jaws are held rigid with respect to each other and the second member is prevented from movement during use.

20 2. A device of the class described and as set forth in claim 1, in which the L-shaped slot has its lateral extension directed away from the stationary jaw, so that the pressure of an article against the movable jaw and acting about the said dog as a fulcrum will retain the stop at the last mentioned end of said slot.

In testimony whereof, I affix my signature.
LINDSAY THORNE CRABBE.
